US00D953811S

(12) **United States Design Patent** (10) **Patent No.:** **US D953,811 S**
(45) **Date of Patent:** ** *Jun. 7, 2022

(54) **TAPERED CUP**

(71) Applicant: **BALL CORPORATION**, Broomfield, CO (US)

(72) Inventor: **Anthony J. Scott**, Westminster, CO (US)

(73) Assignee: **BALL CORPORATION**, Westminster, CO (US)

(*) Notice: This patent is subject to a terminal disclaimer.

(**) Term: **15 Years**

(21) Appl. No.: **29/724,469**

(22) Filed: **Feb. 14, 2020**

(51) LOC (13) Cl. **07-01**

(52) U.S. Cl.

USPC **D7/523; D7/532**

(57) **CLAIM**

The ornamental design for a tapered cup, as shown and described.

DESCRIPTION

FIG. 1 is a front perspective view of the tapered cup; FIG. 2 is a front elevation view thereof, the right, left and rear elevation views being substantially the same as the front elevation view;

FIG. 3 is a top plan view thereof;

FIG. 4 is a bottom plan view thereof;

FIG. 5 is a front perspective view of the tapered cup according to another embodiment;

FIG. 6 is a front elevation view of the embodiment of FIG. 5, the right, left and rear elevation views being substantially the same as the front elevation view;

FIG. 7 is a top plan view of the embodiment of FIG. 5; and, FIG. 8 is a bottom plan view of the embodiment of FIG. 5. The dotted lines showing portions of a tapered cup are provided for the purpose of illustrating environment which form no part of the claimed design.

1 Claim, 6 Drawing Sheets
